(57) **CLAIM**

The ornamental design for a money clip, as shown and described.

DESCRIPTION

FIG. 1 is a top plan view of a money clip showing my new design;

FIG. 2 is a bottom plan view thereof;

FIG. 3 is a side elevational view thereof;

FIG. 4 is a front elevational thereof;

FIG. 5 is a rear elevational view thereof; and,

FIG. 6 is a top plan view showing the present invention positioned about a stack of paper bills.

The indicia or broken lines shown on the figures are for illustrative purposes only and are hereby disclaimed as forming no part of Applicant's claimed invention.

1 Claim, 6 Drawing Sheets
